SURFACING HEAD

Alfred Reineman, New York, N. Y.

Application February 7, 1933, Serial No. 655,549
Renewed November 9, 1934

9 Claims. (Cl. 15—230)

My present invention relates more especially to power driven, manually controlled rotary surface treating implements of the character used for cleaning, polishing, scraping or abrading. While 5 the invention in certain of its broadest aspects is not necessarily limited thereto, the invention finds its preferred field of application where the active cleaning, polishing, scraping or abrading agency generically is of metal wool, preferably 0 steel wool.

Among the objects of the invention are to provide an instrumentality for the above purpose, which precludes contact of any wool holding instrumentality with the surface to be cleaned, polished, scraped or abraded, and yet without danger 5 of the wool slipping relative to the driving holder or coming loose therefrom.

Another object is to provide an instrumentality of the above type, of simple and inexpensive construction to which the wool is easily applied in 0 secure operative relation without the need for any tools other than a conventional wrench.

Another object is to provide an apparatus of the above type, in which while the wool is effectively clamped, the resilience of the wool at the 5 operative abrading or polishing surface is not impaired.

Other objects will be in part obvious and in 0 part pointed out hereinafter.

In the accompanying drawing in which is shown one of various possible embodiments of the several features of the invention,

Fig. 1 shows a perspective view of the implement, partly in section,

Fig. 2 shows a dropped sectional view of the constituent elements of the head prior to assembly,

Fig. 3 is a view in longitudinal cross-section of the head completely assembled, and

Fig. 4 is a plan view of the head viewed from the interior showing the relation of the impaling pins.

Referring now to Figs. 2 to 4 of the drawing, the operating head preferably comprises a bell-shaped wool holder 10, ordinarily of aluminum, preferably formed interiorly as the segment of a sphere and provided with an integral mounting nipple 11. The metal is preferably thicker at the nipple or mounting end or base for strength 5 and tapers off to a thinner rim 12. Affixed in the bell are wool impaling pins 13 of desired number, though ordinarily three such pins are sufficient. These pins are preferably screwed into the head at 14 about an inch from the mounting nipple thereof. The impaling pins, as shown,

are preferably equi-distant and extend obliquely outward toward the rim and obliquely forward with respect to the radial planes of their mounted ends, as shown. While the particular relations are not critical, it is preferable to have the impaling pins extend outward at an angle of about 30 degrees to the vertical and to point forward at an angle of about 60 degrees relative to the radial planes of their bases. Preferably the pins are pointed, as at 15, and their shanks are roughened 10 illustratively by threading as at 13.

In addition to the impaling pins, the head includes a wool retainer preferably in the form of a clamp. This clamp in the preferred embodiment comprises a bolt 17 of brass extending axially of the bell-shaped head and threaded into the base thereof as at 18. The bolt has a wide head 19 thereon provided with a socket 20 for a tightening key (not shown).

The preferred operating material to be embodied in the head described, is steel wool pre-formed as a generally spherical pompon 21 with an axial aperture 22 therethrough. The pompon is readily applied to the head by impaling on the pins 13 therein. This can be done by a direct thrust in which the steel wool will readily find its way over the impaling pins. Thereupon the bolt 17 is inserted through the aperture 22 in the wool pompon and tightened in position until, as shown in Fig. 3, its head has moved past the rim 12 of the holder. In this operation, the wool is wedged into the bell about the impaling pins and between the bolt head and the impaling pins. The axial diameter of the pompon being thus sharply compressed, the wool ball spreads laterally, as best shown in Fig. 3, outward to overlap the rim 12 of the bell, as at 23, and inwardly to overlap the head of the bolt 17, as at 24.

The steel wool installed in its head, as shown in Fig. 3, is quite effectively held. In the rapid rotation of the head, the tendency is for the wool to be forced onto rather than off the impaling pins and the bolt head 19 wedges the wool so tightly in position that it will not accidentally become loose. The threads or irregularities 13 on the impaling pins contribute to the security of attachment of the wool pompon thereto.

The steel wool is so conformed that a generally flat area is provided for treating a flat surface, such as a table, while the rounded rim 23 thereof is effective for access to curved surfaces, corners or the like. The metal wool having been spread, as set forth at its operative regions, the resiliency thereof is not impaired, despite the clamping action of the bolt head 19.

It is obvious that the wool pompon can readily be replaced after it has been worn or sullied. Ordinarily, the wool pompon may be reversed by removal and inserting the opposite part into the bell and exposing for further use, the part that had originally been within the mounting bell.

The wool holding head may be associated with the power driving means in any conventional manner, one such connection being illustratively shown in Fig. 1, where a driving haft 26 is shown threaded at 27 into the nipple 11 and mounting in a socket 28 at the opposite end thereof, the flexible driving shaft 29 which may be driven from any suitable electric motor (not shown). A handle sleeve 30 is telescoped over the haft 26 and held in place thereon by a cap 31 surrounding the flexible shaft and threaded as at 32 on to the upper end of the haft.

It will thus be seen that there is herein described apparatus in which the several features of this invention are embodied, and which apparatus in this action attains the various objects of the invention and is well suited to meet the requirements of practical use.

25 As many changes could be made in the above construction, and many apparently widely different embodiments of this invention could be made without departing from the scope thereof, it is intended that all matter contained in the 30 above description or shown in the accompanying drawing shall be interpreted as illustrative and not in a limiting sense.

Having thus described my invention what I claim as new and desire to secure by Letters 35 Patent is:

1. A rotary metal wool surfacing head comprising a bell-shaped wool holder, impaling pins therein for the wool, and a central clamping member in said head holding the wool in compacted 40 position.

2. A rotary metal wool surfacing head, comprising a bell-shaped wool holder, oblique impaling means therein for the wool extending at an angle to each radius of the head that passes 45 therethrough and a removable headed clamping bolt axially of said holder.

3. A rotary metal wool surfacing head, comprising a bell-shaped holder having a base and a rim, impaling means affixed in said holder and 50 extending obliquely thereof at an angle to each radius of the head that passes therethrough, and a headed bolt extending axially of said holder with the head between said rim and said base.

4. A rotary metal wool surfacing tool, comprising a head having a wool holder, three wool impaling pins extending obliquely outwardly and in the direction of rotation thereof, and means for clamping the wool into the holder.

5. A rotary metal wool surfacing tool, comprising a head having a wool holding bell having a rim, three pointed wool impaling pins within said bell extending obliquely thereof and inclined with respect to the respective radial planes thereof, and a clamping bolt axially affixed in the bell, having a head between the points of the impaling pins and the rim of the bell.

6. A rotary metal wool surfacing tool, comprising a head having a bell with a generally spherical interior, and an axial mounting bushing, a pompon of steel wool therein, a headed bushing bolt axially through said pompon affixed coaxially of said bushing and serving to axially compress the pompon and cause the same to 20 spread laterally to overlap both the head of the bolt and the rim of the bell, said parts being constructed and arranged to resist rotary displacement of the wool pompon relative to the rotating bell.

7. A rotary metal wool surfacing implement, comprising a bell of the form of a spherical segment, having a mounting socket, impaling pins rigid with said socket and extending from near the base thereof, outward toward the rim and 30 obliquely of the respective radial planes of their mounted ends, forward in the direction of rotation of the head, and means to force the wool into the bell.

8. The combination set forth in claim 7 in 35 which the impaling studs have irregular exteriors for further frictional engagement with the metal wool.

9. A rotary metal wool surfacing implement, comprising a bell of the form of a spherical segment, having a mounting socket and a rim, impaling pins rigid with said socket and extending from near the base thereof, outward toward the rim and obliquely of the respective radial planes of their mounted ends forward in the direction of 40 rotation of the head, a pompon of wool impaled on said pins, a mounting bolt coaxially of said socket, compressing the pompon centrally into the bell and causing the excess wool to spread laterally for covering the head of said bolt and 45 overlapping the rim of said bell.

ALFRED REINEMAN.
